E. A. HAWTHORNE,
ILLUMINATING APPARATUS,
APPLICATION FILED JULY 13, 1916.

1,314,590.

Patented Sept. 2, 1919.

Inventor:
Ellsworth A. Hawthorne,
by Emery, Roth, Jamey & Jamey
Attnys.

UNITED STATES PATENT OFFICE.

ELLSWORTH A. HAWTHORNE, OF BRIDGEPORT, CONNECTICUT.

ILLUMINATING APPARATUS.

1,314,590.

Specification of Letters Patent. Patented Sept. 2, 1919.

Application filed July 13, 1916. Serial No. 109,023.

To all whom it may concern:

Be it known that I, ELLSWORTH A. HAWTHORNE, a citizen of the United States, and a resident of Bridgeport, county of Fairfield, and State of Connecticut, have invented an Improvement in Illuminating Apparatus, of which the following description, in connection with the accompanying drawings, is a specification, like characters on the drawings representing like parts.

This invention relates to illuminating apparatus, and is more especially, though not exclusively, concerned with means for eliminating the blinding glare which is usually produced by the type of headlights commonly used for motor vehicles and other similar purposes.

My invention will be best understood by reference to the following description, when taken in connection with the accompanying drawings showing two specific embodiments thereof, while its scope will be more particularly pointed out in the appended claims.

In the drawings:

Figure 1 is a front elevation of one form of illuminating apparatus embodying my invention;

Fig. 2 is a sectional view on line 2—2 of Fig. 1.

Referring to the drawings, and to the embodiment of my invention which is there shown, a lamp casing 1 of any usual or desired form, herein constituting its own reflector of the beam type having a generally parabolic internal surface 2, incloses a suitable source of light 3, herein in the form of an incandescent electric bulb disposed coaxially within the lamp casing. The lamp casing may be, and is herein, provided with a light-transmitting element 4, in the form of a front glass or lens of usual form.

It frequently happens that, with the usual headlights of this type, part of the objectionable glare is produced by the parabolic reflector. This glare usually comes from either the upper or lower portion of the reflector, according to the height at which the lamp is placed on the vehicle. When the lamp is placed at a comparatively low level, the glare usually comes from the lower part of the reflector, and when it is placed high, the glare comes from the upper part. As a means for eliminating such glare, regardless of the height at which the lamp is placed, I have herein provided suitable means which is, in the embodiment shown,

not only adjustable as a whole about the axis but is also extensible and contractible so that its area may be increased or diminished to suit the circumstances. To this end, I have shown a screen comprising a plurality of sections or leaves, herein two in number, designated 11 and 12, respectively, lying in parallel planes and one overlapping the other. These sections or leaves are herein mounted to turn about a common axis, and to that end are provided with co-axially disposed pivots 13 and 14. The pivot 13 is herein in the form of a screw, soldered or otherwise suitably secured to the section 11, while the pivot 14 is herein in the form of a sleeve encircling the pivot 13, and formed either integral with, or soldered to, the section 12.

Both these pivots preferably extend through the light-transmitting element 4, the latter to that end having a central aperture 15, which may be provided with a bushing 16 having a flange 17 interposed between the section 12 and the inner face of the light-transmitting element 4. A nut 18, having screw-threaded engagement with the pivot 14 serves to screw the section 12 in the desired position of adjustment, while a second nut 19, having screw-threaded engagement with the pivot 13, serves to secure the section 11 in the desired position of adjustment, as well as acting as a jam-nut for the nut 18. By simply loosening these nuts, the adjustment of the sections may be accomplished from the outside of the lamp, and the parts secured in the selected position of adjustment. Thus it is apparent that, by the use of two overlapping sections of the screen, the area of the latter may be varied at will, while the position of the screen as a whole may be shifted so as to cut off any portion of the beam.

While I have herein shown and described one specific form or embodiment of my invention for illustrative purposes, and have disclosed and discussed in detail the construction and arrangement of parts incidental to the specific application thereof, it is to be understood that the invention is limited neither to the mere details or relative arrangement of parts, nor to its specific embodiment herein shown, but that extensive deviations from the illustrated form or embodiment of the invention may be made, without departing from the principles thereof.

Having thus described my invention, what I claim and desire by Letters Patent to secure is:

1. An illuminating apparatus comprising, in combination, light-producing means, light-reflecting means associated therewith, light-transmitting means for transmitting the reflected light, light-obstructing means comprising a plurality of overlapping sections provided with pivots extending through said light-transmitting means and means to secure said pivots to said light-transmitting means.
2. An illuminating apparatus comprising, in combination, light-producing means, light-reflecting means associated therewith, light-transmitting means for transmitting the reflected light, light-obstructing means comprising a plurality of overlapping sections provided with coaxially disposed pivots extending through said light-transmitting means, and coaxially disposed means to secure said pivots against turning movement.
- 25 3. An illuminating apparatus comprising

ing, in combination, light-producing means, light-reflecting means associated therewith, light-transmitting means for transmitting the reflected light, light-obstructing means comprising a plurality of overlapping sections provided with coaxially disposed pivots extending through said light-transmitting means, and fastening means for said pivots comprising elements threaded onto said pivots respectively. 30 35

4. A lamp comprising a casing, a glazing therefor and a light therein, said glazing presenting a pivot bearing substantially in line with said light, a substantially sector shaped screen within the case having a sleeve journaled in said bearing and projecting exteriorly of the glazing, a nut coöoperating with said sleeve, a second screen having a pivot pin journaled in said sleeve and projecting beyond the same and a nut for said pin. 40 45

In testimony whereof I have signed my name to this specification.

ELLSWORTH A. HAWTHORNE.
